UNITED STATES PATENT OFFICE.

CARL G. HEIBY, JOHN BURKAM, DAVID E. LINDQUIST, FRED L. RIGGIN, EBENEZER W. ALLEN, AND RICHARD LAU, OF SARNIA, CANADA, ASSIGNEES, BY MESNE ASSIGNMENTS, TO MUELLER METALS COMPANY, OF PORT HURON, MICHIGAN, A CORPORATION OF MICHIGAN.

MOLD FOR CASTING METAL BARS.

1,331,920.

Specification of Letters Patent. Patented Feb. 24, 1920.

Application filed January 17, 1918. Serial No. 212,224.

To all whom it may concern:

Be it known that we, CARL G. HEIBY, JOHN BURKAM, DAVID E. LINDQUIST, EBENEZER W. ALLEN, FRED L. RIGGIN, and RICHARD LAU, all citizens of the United States except ALLEN, a subject of Great Britain, residing at Sarnia, in the county of Lambton and Dominion of Canada, have invented new and useful Improvements in Molds for Casting Metal Bars, of which the following is a specification.

The present invention relates to new and improved apparatus for casting, more particularly the casting of stock for use in drop 15 forging.

Stock for forging must be free from faults, such as blow holes, pipes, and dross fillings, for the reason that not only will such faults appear under the action of the 20 press, but also where such forgings are afterward machined sub-surface faults may be developed. Such faults result in much stock that cannot be used, and many of the forgings, both before and after machining, 25 are so faulty as to be rejected, with the consequent loss of material and labor. Furthermore, faults not apparent after forging or machining may develop in use, necessitating the removal of the defective article and its 30 replacement by a sound one.

This has been so serious a difficulty that much of the stock is produced by the expensive method of rolling, so as to eliminate the objectionable porosities which, as stated, 35 are common in castings made under present methods.

With the apparatus herein disclosed it is possible to produce stock free from the faults named, and equal to the rolled stock, expeditiously and cheaply, so that finished articles 40 may be turned out in large numbers and at a relatively low cost, with practically no loss from rejected stock or finished goods.

While the stock produced may, of course, 45 be utilized for any purpose, the present embodiment of the invention discloses the manufacture of stocks designed more particularly for the rapid and economical production of fuse bodies for shells, which must, 50 first, be of high grade material to insure efficiency and safety, and second, must be produced economically and expeditiously.

In the drawings herewith is shown one

physical embodiment of the apparatus and by which the method may be practised, and 55 in said drawings:

Figure 1 is a longitudinal sectional view of molding apparatus made in accordance with this invention;

Fig. 2 is a top plan view of the apparatus 60 shown in Fig. 1;

Fig. 3 is a section transversely of the apparatus on substantially the line 3—3 of Fig. 1, looking in the direction of the 65 arrow;

Fig. 4 is a view similar to that shown in Fig. 3 with the mold or chill open;

Fig. 5 is a perspective view of the clamp and wedge block for clamping the upper and 70 lower parts of the chill.

Referring to the drawings by numbers, the same numbers indicating like parts in the several views, 10 indicates the lower half of a mold or chill, which is channeled or grooved to the particular shape in cross-section of the stock to be produced. The chill member 10 is mounted on any suitable support, as for example blocks 11.

Seated upon said chill member 10, and for convenience hinged thereto, is a complementary upper chill member 12, grooved to coincide with the groove in the member 10, so that when the parts are closed a proper mold cavity is formed.

The two members 10 and 12 may be suitably clamped together by U-clamps 13 and wedges 14, as shown, or by any usual and readily removable device.

The member 10 is preferably extended as at 15 and somewhat thickened, a chamber 90 16 being formed in such extension, the bottom of which is below the bottom of the groove in the lower member 10, while the upper surface of the extension 15, which forms a seat for a sprue block 17 is in a plane 95 below the top of the groove in member 12. Mounted upon the extension 15 is the sprue block 17, which is preferably made in two half-portions, as shown, so as to form a vertical channel delivering to the chamber 16 100 heretofore described.

The chamber 16 is preferably provided with a curved bottom which slopes easily to the bottom of the mold cavity in the chill.

The said sprue block members are held 105 together by any suitable means, as a screw-

clamp 18, and are clamped tightly to the seat formed by the extension 15 by a clamp 19 which may be tightened by wedge blocks 20.

- 5 Preferably the sprue hole formed by the vertical members of the block 17 which constitutes a mold-supplying container is coned or tapered from the bottom upwardly, so as to give freedom of flow to the chamber 10 16 and a substantial supply of metal, while giving a minimum surface of metal exposed to oxidization at the top of the sprue hole.

The upper chill member 12 is provided with means for venting the mold, and it is 15 obvious that this venting means may take various forms. In the form shown, it is illustrated as a narrow slot 22 extending lengthwise of the upper chill member 12, but it is obvious that the venting might be 20 secured by means of a series of orifices or slots arranged longitudinally of the chill member 12 with good results, the purpose of this vent orifice being to permit the ready escape and venting of gases from the mold 25 interior as the molten metal flows into the mold. The venting means herein shown as a slot 22, has the further advantage that when the metal is poured, the slot 22 will receive an excess of metal, and as the bar 30 or casting begins to set or freeze, and by reason of such freezing, shrink or contract, this excess metal which flows upwardly into the slot 22 will collapse into the bar and supply a small excess of metal to insure a 35 full sized and solid casting without leaving any objectionable fin or projection along the line of the slot.

As has been stated the chill members 10 and 12 are clamped by the U-members 13 40 and wedges 14, and if the venting means consists of the slot 22 extending the full length of the chill member 12, as shown in the present illustration, the wedges 14 will preferably be formed as shown, slotted and 45 grooved so as not to interrupt the continuity of the slot 22, and prevent free venting.

With the parts disposed as shown and described, it will be seen that a chill is provided in which a closed molding cavity is 50 provided to which the metal is delivered from a pool collected in an enlarged chamber at the receiving end of the chill cavity. Flow from the chamber to the mold cavity is through the somewhat restricted passage 55 formed by the lower end of the vertical sprue block, which lower end serves to dam and hold back dross and floating impurities and prevent their passing into the mold cavity. As the molten metal is poured into the 60 sprue it will, of course, fall to the bottom of the chill-supplying chamber and the flow will be from the bottom of the pool along the sloping surface leading into the mold cavity, so that pure metal only will be delivered. By maintaining an excess of metal 65

in the container so that the height of the poured metal in the chamber and sprue hole will be above the level of the passage leading to the chill cavity, all dross or other impurities are skimmed back and held in the 70 vertical sprue hole so that their passage to the mold is impossible.

If desired the end of the chill may be stopped by a plug 21 which is placed at any desired point longitudinally of the mold 75 cavity and will be securely held when the chill members are clamped together.

When the run has been made and the metal has set and cooled the chill parts will be unclamped and separated and the casting 80 removed. It will be of the form shown as filling the mold cavity in Fig. 1, with a body portion of pure dense metal free from faults, at the sprue end of which will be the vertical portion formed by the sprue block. The 85 relatively small vertical portion will contain those impurities which have been skimmed back and prevented from entering the mold, and may be readily separated at the relatively thin section by which it is joined to 90 the main casting.

We claim:

1. A mold comprising a plurality of horizontally separable chill members, one of which is provided with a venting orifice and the other of which has a chambered extension, a sprue block formed of a plurality of vertically separable members mounted on said extension and in communication with said chill members, said sprue block forming therewith a restricted passage from said chamber to said mold. 95

2. In a mold, a plurality of horizontally separable chill members, the upper one of which has a venting orifice, means for 105 clamping said members together, an extension on the lower one of said chill members having a chamber extending below the bottom of the mold, a sprue block formed of a plurality of vertically separable members seated on said extension and forming therewith a restricted passage from said chamber to said mold, means for clamping said sprue block member together, and means for clamping said members to the chill extension. 110

3. In a mold, a lower chill member, an upper chill member hinged thereto and having a venting orifice, an extension on the lower chill member having a chamber extending 120 below the bottom of the mold, means for clamping said hinged members together, a sprue block formed of a plurality of members mounted on said extension and forming with said extension a restricted passage to 125 said mold, means for clamping said block members together, and means for clamping said sprue block to its seat.

4. In a mold, separable chill members, one of said members having a venting orifice, 130

clamps for holding said members together, and wedges for seating said clamps having openings coinciding with the venting orifice.

5. In a mold, a lower chill member, an upper chill member having a venting slot therein, clamps for holding said chill members together, and wedges for seating said clamps having grooves and openings therein coinciding with the venting slot in said

10 upper chill member.

6. A mold comprising a plurality of horizontally separable chill members, one of which is provided with a venting orifice and the other of which has a chambered exten-

sion, a sprue block formed of a plurality of 15 members mounted on said chill members, said sprue block forming therewith a restricted passage from said chamber to said mold.

In testimony whereof we have hereunto 20 set our hands.
